CLAIM

The ornamental design for a hunt camera, as shown and described.

DESCRIPTION

FIG. 1 is a perspective view of a hunt camera showing my new design;

FIG. 2 is another perspective view of FIG. 1;

FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1;

FIG. 8 is bottom view of FIG. 1; and,

FIG. 9 is an enlarged view of the selected portion in FIG. 1. The broken lines illustrate portions of the hunt camera that form no part of the claimed design.

1 Claim, 9 Drawing Sheets(56)
